(57) **CLAIM**

The ornamental design for an ornamental garden cannon, as shown and described.

DESCRIPTION

FIG. 1 is a perspective view of an ornamental garden cannon, showing my new design;

FIG. 2 is a front elevational view thereof;

FIG. 3 is a rear elevational view thereof;

FIG. 4 is a left side elevation thereof, the right side elevation being a mirror image;

FIG. 5 is a top plan view thereof; and,

FIG. 6 is a bottom view thereof.
